CUTTING DEVICE FOR BUTTONHOLE- OR
OTHER SEWING MACHINESHermann Pudelko, Bielefeld, Germany, assignor
to Dürkoppwerke Aktiengesellschaft, Bielefeld,
GermanyApplication September 24, 1934, Serial No. 745,183
In Germany September 30, 1933

2 Claims. (Cl. 112—68)

This invention relates to a cutting device for buttonhole- or other sewing machines. It is known to positively push the knife of such machines into the material for the purpose of cutting and to pull it back into its inoperative position by a spring after the cutting operation. It is likewise known to push the knife into the material and to positively pull it out of the material, the knife being operated by a cam disc. Compared herewith the invention consists in that the knife is positively driven into the material for cutting and also positively pulled out of the material after the cutting, the lever transmission actuating the knife being actuated by a crank 15 driven from the main driving shaft through the intermediary of a cam, and a safety device being provided which allows the knife only to become operative when the cloth feeder is in the correct position and when the button hole is finished. This is attained according to the invention in that the system of levers actuating the knife is coupled with a pivotally mounted lever moved up and down from the main driving shaft through the intermediary of a cam in such a manner that the knife is positively driven into the material for cutting and positively pulled out of the material, the coupling being controlled by a cam disc and secured against premature coupling by means of a safety device.

An embodiment of the invention is illustrated by way of example in the accompanying drawing, in which:—

Fig. 1 shows the machine with the cutting device in side elevation.

Fig. 2 is a top plan view of Fig. 1.

Fig. 3 shows a portion of the coupling lever in side elevation.

Fig. 4 is a part side elevation of the safety device for preventing premature coupling.

A knife 1 is arranged on a rod 2 and guided on a bar 3. The rod 2 is actuated by a system of levers 4, 5, 6, 7. The lever 7 is moved by a coupling arm 8 which is returned into its inoperative position shown in the drawing by means of a spring 9. The coupling arm 8 has a projection 10 on which a rod 11 bears in inoperative position. Discs 12 and 13 are fixed on this rod 11, whereas a disc 14 is loosely mounted thereon. A spring 15, situated between the discs 12 and 14, tends to maintain the rod 11 in the position illustrated. A rocker lever mounted in a bracket 16 bears with one arm 17 against the disc 13 and with its other arm 18 against a cam disc 20 keyed on a shaft 19. The shaft 19 is driven in known manner at a suitable ratio of transmission from

the main driving shaft 21 through the intermediary of gear wheels 21, 22, 23, 24, 25, 26. As the arm 18 slides on the cam disc 20, which rotates in the direction of the arrow x, the disc 13 and therefore the rod 11 will be shifted by the arm 17 in the direction of the arrow y against the action of the spring 15. The rod 11 mounted in a bearing 28, owing to this shifting movement in the direction y, slides off the extension 10 and drops into the position indicated in dot-dash lines in Fig. 1. This bearing is rigid with a bracket 40 fixed on the machine frame and the disc 14 is loosely mounted on the rod 11. Consequently the disc 14 is pressed by the spring 15 against the end of the bearing 28 and serves as an abutment for the spring 15. The spring 15 might bear directly against the end of the bearing 28 but as the rod 11 must swing up and down and must consequently fit relatively loosely in the bearing 28 it is advisable to interpose the disc 14 between the bearing 28 and the spring 15. The rod 11 is not mounted in a bearing at its other end because it must be able to move up and down with the end resting on the extension 10 of the lever 8. Only a bracket 41 is provided, as shown in Figs. 1 and 2, which bracket serves for preventing the rod 11 from dropping too far when it slides off the extension because the rod must rest in its lower position against the plate on the lever 8. When a tooth 29 on the cam disc 20 has passed the arm 18, the pressure exerted by the arm 17 against the disc 13 suddenly ceases, so that the rod 11 tends to return into its initial position under the action of the spring 15. The rod 11, which is in the position shown in dot-dash lines, will press the nose 30 of the lever arm 8 towards a bore 33 in an oscillatable strap 32. This strap 32 is pivotally mounted in a bracket 34 and is continually moved up and down from the main driving shaft 21 through the intermediary of a cam 36. During this up and down movement the nose 30 on the arm 8 is pressed by the rod 11 towards the bore 33 in which it cannot, however, immediately engage owing to the safety bar 37. After this pressure is exerted the arm 31 must first complete its downward movement. During the upward movement the bar 37 is pressed away from the bore 33 by the nose 30 against the action of the spring 38, so that the nose 30 can engage in the bore 33. The knife 1 is thus positively coupled with the driving shaft 21. During the next downward movement of the arm 31 the material is pierced by the knife 1 and during the succeeding upward movement it is pulled out of the material. The spring 9, 55

as already mentioned, returns then the coupling lever 8 with the nose 30 into their initial positions.

I claim:—

- 5 1. A cutting device on button hole and similar sewing machines, comprising in combination with the machine frame, a knife vertically reciprocable in said frame, a lever system connected with said knife, a main driving shaft journalled in said frame, a cam on said shaft, a crank actuated by said cam, a strap pivotally mounted on said frame and oscillatable by said crank, a counter shaft driven by said main shaft, a second cam rotated by said counter shaft, said strap having a bore, a coupling lever pivotally connected at one end with said lever system, a nose on the other end of said coupling lever adapted to engage the bore in said strap, a guide rod slidably mounted on said machine frame, a two-armed lever bearing with one arm against said second cam and engaging with its other arm said guide rod, said guide rod adapted to be longitudinally shifted to the right by said cam, a spring on said guide rod, adapted to press said guide rod against said coupling lever and to oscillate said lever to cause said nose to engage said bore when the cam releases said rod, and a locking device on said strap adapted to prevent premature engagement of said nose in said bore.
- 10 10
- 15 15
- 20 20
- 25 25

2. A cutting device on button hole and similar sewing machines, comprising in combination with the machine frame, a knife vertically reciprocable in said frame, a lever system connected with said knife, a main driving shaft journalled in said frame, a cam on said shaft, a crank actuated by said cam, a strap pivotally mounted on said frame and oscillatable by said crank, a counter shaft driven by said main shaft, a second cam rotated by said counter shaft, said strap having a bore, a coupling lever pivotally connected at one end with said lever system, a nose on the other end of said coupling lever adapted to engage the bore in said strap, a guide rod slidably mounted on said machine frame, a two-armed lever bearing with one arm against said second cam and engaging with its other arm said guide rod, said guide rod adapted to be longitudinally shifted to the right by said cam, a spring on said guide rod adapted to press said guide rod against said coupling lever and to oscillate said lever to cause said nose to engage said bore when the cam releases said rod, and a movable bar on said strap, and a spring supporting said bar so that it covers said bore, said bar adapted to yield against the action of said spring under the pressure of said nose during the oscillation of said strap to allow the engagement of said nose in said bore.
